UNITED STATES PATENT OFFICE

CHARLES J. KAYKO, OF JACKSON, MICHIGAN, ASSIGNOR, BY MESNE ASSIGNMENTS, TO THE SPARKS-WITHINGTON COMPANY, OF JACKSON, MICHIGAN, A CORPORATION OF OHIO

VACUUM TUBE

Application filed May 21, 1928. Serial No. 279,594.

This invention relates to certain new and useful improvements in vacuum tubes, and more particularly to those tubes, the cathodes of which are heated by alternating current.

One of the objects of my invention is to produce a tube which is easily exhausted and does not have an excessive amount of insulating material which makes this process difficult.

Another of the objects of my invention is to provide a type of construction which is rugged and will not go out of shape easily.

Another of the objects of my invention is so to choose the material of which the heater is made that electrons will be emitted from it with difficulty, thereby minimizing hum when alternating current flows through the heater.

How I accomplish these results is clearly set forth in the following specification.

Figure 1 is a sectionalized view of my tube in which —1— is a carbon helix secured to supporting and conducting members 6.6 by clamp paste shown at 5.5.

—2— is a carbon rod covered with emitter material, such as an alkaline earth oxide or oxides also secured to a conducting and supporting member —7— by clamp paste. The tip of part —2— (the emitter and cathode) projects a short distance beyond the helical heater —1—.

A screen grid —3— horizontally disposed above the emitter is welded to a conductor and support —8— and for stiffness is also welded to a wire —13— projecting from the insulating bead —9— melted on the plate-support —10—.

Above the grid welded to supports —10— and —11— is a plate —12— in the form of a round disk of suitable metal.

The operation of this very simple tube is as follows: Alternating current is fed into the heating helix —1—. It should be noticed that this heater coil is not connected to the so-called "radio" parts of the tube. The rod —2— will now be heated by radiation. Since this is the grid return (cathode) electrons will flow from this to the plate —4—.

The varying potential gradients along the helix will not disturb the operation of the tube for the emitter is efficient. The plate

current can easily be made very large, but very little current comparatively would flow from the hot helix to the plate even if the helix were in the grid return circuit. This is because carbon emits electrons only at very high temperatures and high potentials; in other words, it is an inefficient emitter. Added to the fact that the heating helix forms no part of the "radio" circuits, what few electrons come off the heating helix are smothered in the flow of electrons from cathode to anode. Their effect, if any, is so small that no hum can be heard even in multi-stage amplifiers.

I choose carbon as a heating material for the above and for the following reasons. Its electron emission is extraordinarily low, it will not sag and go out of shape as do metal filaments and its resistance is so much higher than metal that fairly high "filament" voltages may be conveniently used. This feature is valuable both in cutting down size of the filament leads and making drop-wire operation from 110 volts D. C. lighting mains practical.

I choose carbon as a support for the oxide emitter coating because the insulation of this tube depends on the maintenance of the space relationship between heating helix and emitter rod. A metal rod has a greater tendency to warp.

It will thus be seen that I have produced a very simple device which makes A. C. operation of radio tubes practical. I have eliminated, too, many aggravating points in the manufacture of such tubes, such as the degassing of porcelain insulators, etc. The small amount of material in the tube makes pumping a simple process.

I have illustrated the actual tubes I have made. It is, of course, obvious to those skilled in the art that the geometrical arrangement of the parts may be widely varied and yet produce precisely the same results.

I claim:

1. An electron discharge tube comprising a bulb, a press, a carbon rod cathode supported at one end, a helical carbon heater surrounding said cathode in part but out of electrical contact therewith, a grid electrode

positioned above said cathode, a plate electrode in spaced parallel relation to said grid electrode, and leads through said press connected to said electrodes and said heater, said 5 leads also serving as supporting means for said electrodes and said heater.

2. An electron discharge tube comprising a bulb, a press, a carbon rod cathode supported at one end and having an electron 10 emitting coated portion on the other end, a helical carbon heater surrounding said cathode in part but out of electrical contact therewith, a grid electrode positioned above said cathode, a plate electrode in spaced parallel 15 relation to said grid electrode, and leads through said press connected to said electrodes and said heater, said leads also serving as supporting means for said electrodes and said heater.

20 In witness whereof I have hereunto set my hand this 12 day of May, 1928.

CHAS. J. KAYKO.
